ABSTRACT OF THE DISCLOSURE

The invention provides an electronic circuit which can both be readily integrated and be of very low power consumption and in which circuit the active components consist essentially of insulated-gate field-effect transistors of same conductivity type and the passive components consist essentially of capacitors, the integrated circuit being featured by at least one elementary voltage-amplifying circuit having therein a pair of said transistors and a said capacitor, and supplied by a periodic voltage source.

This application is a continuation-in-part of my application Ser. No. 441,975, filed Mar. 23, 1965.

The present invention relates to a low power consumption integrated electronic circuit.

According to the present invention there is provided an integrated electronic circuit consisting essentially of insulated-gate field-effect transistors of the same conductivity type and of capacitor structure electrically connected in a predetermined circuit arrangement, each of said transistors having first and second electrodes in a conduction path, and a gate electrode for controlling the conductivity of the path, said electrodes being formed on one face of a body of semiconductive material and said first and second electrodes of the transistors having rectifying junctions with said body, and said capacitor structure including a capacitor having first and second electrodes and a dielectric between said first and second electrodes thereof, said capacitor electrodes and dielectric also being formed on said one face of said body, there being a voltage-amplifying elementary circuit having therein a pair of said transistors and said capacitor, the first electrodes of said pair of transistors and of said capacitor being connected to one another, the second electrodes of one of said pair of transistors and of said capacitor being adapted to be connected to the terminals of a periodic supply voltage source, the gate electrode and the second electrode of said one transistor providing the input of said voltage-amplifying elementary circuit and being adapted to be connected to the terminals of a control voltage source, the gate electrode of the other of said pair of transistors being connected to the second electrode of said capacitor, and the second electrodes of said pair of transistors being in the output of said voltage-amplifying elementary circuit.

The circuit according to the present invention is an improvement in the circuits disclosed in my application Ser. No. 441,975 insofar as the voltage-amplifying elementary circuit is able rapidly to charge, when necessary, in the absence of a control (input) voltage to the gate of its first transistor, a capacitor of low capacitance to a voltage having a value very close to the maximum value of the voltage appearing at the output of the elementary circuit, and for this capacitor to remain charged until the appearance of a control voltage of sufficient value.

Identification of drawings

In the accompanying drawings:

FIGURE 1 shows the electrical arrangement of a voltage-amplifying elementary circuit which according to the present invention is integrated;

FIGURE 2 shows, in perspective, the circuit of FIGURE 1 in integrated form;

FIGURE 3 is a section along line III—III of FIGURE 2;

FIGURES 4 and 5 are two explanatory graphs in connection with the elementary circuit of FIGURE 1;

FIGURE 6 is an electrical diagram of a first bistable set-reset circuit, which circuit includes two elementary circuits according to FIGURE 1;

FIGURE 7 is an electrical diagram of a second bistable set-reset circuit, which circuit includes one elementary circuit according to FIGURE 1;

FIGURES 8, 10 and 12 is an electrical diagram of three different frequency dividing circuits, each including one elementary circuit according to FIGURE 1;

FIGURES 9a to 9e, 11a to 11f, and 13a to 13e show sixteen explanatory graphs in connection with FIGURES 8, 10 and 12;

FIGURE 14 is an electrical diagram of a multi-stage frequency divider; and

FIGURES 15a to 15e show six explanatory graphs in connection with the FIGURE 14 circuit.

Disclosure of embodiments

The voltage-amplifying elementary circuit shown in FIGURE 1 comprises a first insulated-gate field-effect transistor T₁ which is connected, in series with a capacitor C₁, to a source S₁ supplying a driving periodic voltage v_o. Point I, which couples an electrode 1 of transistor T₁ and an electrode 3 of capacitor C₁, is connected to an electrode 5 of a second transistor T₂ whose other electrode 6 is connected to the output 7. The gate electrode 8 of transistor T₁ is connected to an input 10, whereas the gate electrode 9 of transistor T₂ is connected to source S₁. The second electrode 2 of transistor T₁ is earthed.

FIGURE 2 shows the above-described elementary circuit in integrated form. It is formed on one face of a semiconductive monocrystal which, in the present instance, is a monocrystal 11 of N-type silicon. The electrodes of transistors T₁ and T₂ and one electrode of capacitor C₁ are formed by P-type zones diffused into the crystal 11. The electrode 1 of transistor T₁, the electrode 5 of transistor T₂ and the electrode 3 of capacitor C₁ are formed by a common zone 135. The second electrode 2 of transistor T₁ is formed by zone 2, with the second electrode 6 of transistor T₂ being formed by zone 6. Three other zones 12, 13 and 14 are moreover formed in the same face of monocrystal 11 but are of N⁺-type. The function of zone 12 is to enable the earthing of crystal 11 and the function of zones 13 and 14 being to prevent the build-up of inversion zones beneath the transistor gate connections. On the silicon oxide insulating layer 15 are deposited metallic layers which provide the gates 8 and 9 of transistors T₁ and T₂ and the second electrode 4 of capacitor C₁. Another layer 16 provides the ohmic contact for zones 2 and 12 to earth the electrode 2 of transistor T₁ and the monocrystal 11.

The above-described elementary circuit operates as follows:

In order that this operation may more readily be understood, consideration will first be given to the part made up of transistor T₁ and of capacitor C₁, i.e. without transistor T₂, to see what voltage v₁ would be in relation to the input (control) voltage v_e.

It will be assumed that source S₁ delivers unidirectional trapezoidal voltage impulses, as shown in FIGURE 4,

and that the threshold voltage of transistor T_1 is larger than that of the PN junction formed by zone 135 with monocrystal 11. If the control (input) voltage V_e is zero, the output voltage V_1 then practically varies between 0 and V_o , because of the effect of this junction PN, and corresponds, as regards shape, to voltage v_o (see curve X in FIGURE 5). If voltage v_e is now applied and is progressively increased, voltage v_1 will progressively decrease and its shape will progressively change as shown by curves Y and Z in FIGURE 5. In view of this change in the shape of voltage V_1 , various circuit amplification factors can be defined depending on whether it is the peak value, the mean value or the effective value of voltage v_1 that is being referred to.

In the following, reference will be had to the peak value which is the most important for the operation of electronic circuits comprising one or more elementary circuits.

Under current saturation conditions for transistor T_1 , this peak value is

$$V_{1p} = A \cdot t_o - \frac{I_s \cdot t_o}{C_1}$$

wherein

$$A = \frac{dv_o}{dt} = \frac{V_o}{t_o}$$

and

$$I_s = K'(V_o - V_{eo})^2$$

V_{eo} being the threshold voltage of transistor T_1 and K' being a constant which depends on the geometry of transistor T_1 .

To obtain $V_{1p} = 0$, it is necessary to have

$$I_s = AC_1$$

such being the case when the control voltage v_e will at least be

$$v_e = \sqrt{\frac{AC_1}{K'}}$$

By carefully choosing values A , C_1 and K' , it is possible to arrange for this value of v_e to be much smaller than that of voltage v_o .

The circuit will now be considered as a whole, i.e. including transistor T_2 . Moreover, it will be assumed that a capacitor C_2 , shown in dotted lines and having a capacitance much smaller than that of capacitor C_1 , is connected to the output 7 of the circuit.

If it is supposed that voltage v_e is zero and that the capacitor C_2 is discharged, a voltage v_o impulse will then as a result give rise to a voltage v_1 having practically the same value as v_o and will moreover give rise to a control voltage for transistor T_2 , across its gate 9 and its electrode 6 which forms its source. This transistor T_2 will thus be rendered conductive, thereby causing capacitor C_2 to be charged by the output voltage v_s whose maximum value will amount to the difference between V_o and V_{eo} (the threshold voltage of transistor T_2). When this maximum value of V_s will have been reached, transistor T_2 will be blocked as its control voltage will then be equal to its threshold voltage. A reduction of voltage v_o will cause this control voltage of transistor T_2 to decrease still further so that transistor T_2 will remain blocked and no discharge of capacitor C_2 will, as a result, be able to occur.

If now an input voltage v_e having a value greater than

$$\sqrt{\frac{AC_1}{K'}}$$

is applied, transistor T_1 will become conductive, so that the next v_o impulse will cause the control voltage of transistor T_2 to appear, but this time across its control electrode 9 and the electrode 5 which will now act as its source. Transistor T_2 will thus be rendered conductive and this will bring about the discharge of capacitor C_2 via the two transistors T_2 and T_1 .

As will be appreciated, the above-described elementary circuit may be used as an A.C. to D.C. controlled converter when source S_1 is an alternating voltage or bi-directional impulse source.

- 5 The bistable set-reset circuit of FIGURES 6 consists of two voltage-amplifying elementary circuits similar to that shown in FIGURE 1, namely T_1 , C_1 , T_2 and T_1' , C_1' , T_2' . These circuits are supplied by the same source S_1 and are so connected that the input and the output of one circuit 10 may be respectively connected to the output and to the input of the other circuit. Further, each of the two circuits comprises a third transistor, respectively T_3 and T_3' , connected in parallel to the first transistor, respectively T_1 and T_1' , the gate of this third transistor being intended 15 for connection to a control voltage, respectively v_e and v_e' . The capacitors C_p and C_p' are essentially formed by the input capacitance of transistors T_1' and T_1 respectively.

The operation of this set-reset circuit will readily be 20 understood from the explanations given above in connection with the operation of the elementary circuit of FIGURE 1. Depending on whether it is control voltage v_e or v_e' that is being applied, the circuit is placed in one or other of its stable states.

- 25 The bistable set-reset circuit of FIGURE 7 differs from that shown in FIGURE 6 in that one of the elementary circuits is of the kind disclosed in our above mentioned patent application Ser. No. 441,975, filed Mar. 23, 1965, i.e. one consisting of a transistor T_1' and of a capacitor C_1' , the other elementary circuit, i.e. T_1 , C_1 , T_2 being as before similar to that shown in FIGURE 1 herein. As in the previous case, each of these two circuits comprises a further transistor in parallel with the input transistor, respectively T_3 and T_3' .

30 35 The circuit operates in a manner similar to the FIGURE 6 circuit except that there is a preferential stable state, i.e. a stable state to which it will always pass, under the action of v_o , when both capacitors C_p and C_p' are discharged. It may be used with advantage as a memory 40 in a frequency dividing circuit, as will be explained later.

The frequency dividing stage shown in FIGURE 8 comprises a voltage amplifying circuit T_2 , C_2 , T_3 , similar to that of FIGURE 1, and two elementary circuits each consisting of a transistor and of a capacitor, respectively T_1 , C_1 and T_4 , C_4 .

- 45 50 55 The input and the output of circuit T_2 , C_2 , T_3 are respectively connected to the output of circuit T_1 , C_1 and to the input of circuit T_4 , C_4 with the output of the latter being connected to the input of circuit T_1 , C_1 . The three circuits are supplied by source S_1 which delivers a periodic voltage v_o in the form of trapezoidal impulses. This voltage also constitutes the input voltage v_e whose frequency is to be divided. This frequency dividing stage operates as follows:

It will be assumed that capacitor C_p , formed by the 55 input capacitance of transistor T_4 , is charged so as to be current conductive, whereas transistor T_1 is blocked.

- A voltage v_o impulse delivered by source S_1 will cause 60 this voltage v_o to appear at point I, and this in turn will cause transistor T_2 to become conductive and cause the discharge of capacitor C_{pn} via transistors T_2 and T_3 . The mutual conductance of transistor T_2 being slight in relation to that of transistor T_4 , the time taken for the discharge of capacitor C_p will be longer than t_0 (see FIGURE 4) so that no voltage will appear at point IV, and hence no voltage v_s will appear at the output 17 of the dividing stage, before the next voltage v_o impulse. The latter will thus cause the transistor T_1 to become conductive, the transistor T_2 to be blocked, the voltage to appear at point II and the capacitor C_p to be recharged. The mutual conductance of transistor T_3 being less than that of transistor T_4 , the recharging of capacitor C_p will take longer than t_0 (FIGURE 4), thereby enabling a voltage v_s impulse to appear at output 17.

70 75 Consequently, as will be apparent from the above, there

will only be one voltage v_s impulse at the output 17 of the dividing stage for every two voltage v_o impulses at the input 21. The frequency of the latter voltage is thus halved.

FIGURES 9a to 9e show, respectively, voltages v_o , v_I , v_{II} , v_{III} and v_{IV} .

In this dividing stage, the input (control) voltage v_e , whose frequency is to be divided, and the supply voltage v_o are identical. Although the capacitor C_2 , forming the memory of the dividing stage, is not likely to be prematurely discharged by reverse junction currents when the frequency is medium or high, the same does not hold true when the frequency is very low. In this latter case it is necessary to provide a supply current having a frequency greater than that of the control voltage so that the capacitor C_p may be recharged by the supply voltage during one period of the control voltage.

The dividing stage of FIGURE 10 is for very low frequencies. As will be observed, this dividing stage comprises a bistable circuit which is similar to that shown in FIGURE 7 and which consists of two elementary circuits, the first, which is similar to that of FIGURE 1, comprising two transistors T_3 , T_5 and a capacitor C_3 , and the second comprising a transistor T_6 and a capacitor C_6 . The two circuits are supplied with a common voltage v_o provided by a source S_1 . The output of the first circuit T_3 , C_3 , T_5 is, on the one hand, connected to the input of the second circuit T_6 , C_6 , and is, on the other hand, earthed via a transistor T_2 . The gate of this transistor T_2 is connected to the output of a third elementary circuit which comprises a transistor T_1 and a capacitor C_1 and which is supplied by a source S_2 providing the input (control) voltage v_e . The gate of transistor T_1 is connected to the output of the second elementary circuit T_6 , C_6 via a transistor T_7 whose gate is connected to source S_1 . The output of this second circuit T_6 , C_6 moreover is, on the one hand, connected to the input of the second circuit T_3 , C_3 , T_5 and is, on the other hand, earthed via a transistor T_4 whose gate is connected to source S_2 . In the case under consideration, the frequency of voltage v_o is twice that of voltage v_e .

This dividing stage operates as follows:

It will be assumed that capacitor C_p is discharged, so that transistor T_6 is blocked. A voltage v_o impulse from source S_1 will cause a faster increase of the control voltage of transistor T_3 than that of transistor T_6 . Transistor T_3 being then rendered conductive, capacitor C_p will therefore remain discharged and transistor T_6 blocked so that voltage v_o will appear at point IV and consequently voltage v_s will appear at the output 18 of the dividing stage. This will also result in capacitor C'_p being charged via transistor T_7 and hence in transistor T_1 in becoming conductive. At the next voltage v_o impulse, which is delivered simultaneously with a voltage v_e impulse, no voltage will appear at point I since transistor T_1 is conductive. On the other hand, however, transistor T_4 will become conductive thereby causing transistor T_3 to be blocked. With transistor T_2 also blocked, voltage v_o will therefore appear at point II, thereby causing capacitor C_p to be charged via transistor T_5 , transistor T_6 to become conductive, capacitor C'_p to be discharged via transistors T_7 and T_4 , and transistor T_1 to be blocked. The dividing stage will remain in this state despite leakage currents since capacitor C_p is recharged by the next impulse voltage v_o . At the next impulse of voltage v_e , the latter will appear at point I since transistor T_1 is blocked. This will cause transistor T_2 and T_4 to become conductive, so that no voltage will appear at points II and IV and hence at the output 18 of the dividing stage. At the next impulse of v_o alone, the dividing stage will be returned to its starting state. Consequently, as will be apparent from the above, for every two impulses of voltage v_e at the input 23 there will only be one impulse of voltage v_s at the output 18 of the dividing stage circuit.

FIGURES 11a to 11f respectively show the voltages v_o , v_e , v_I , v_{II} , v_{III} and v_{IV} .

The two above-described dividing stages, illustrated in FIGURES 8 and 10 respectively, each have a dividing factor of two. It is often of advantage, when having to divide very high frequencies, to have dividing stages available having a larger dividing factor.

FIGURE 12 shows a frequency dividing stage with which a higher dividing factor can be obtained. This stage consists of an elementary circuit T_1 , C_1 , T_2 , similar to that of FIGURE 1, and of an elementary circuit T_3 , C_3 . The output of the first circuit T_1 , C_1 , T_2 is connected both to the input of a transistor T_4 , which grounds the input of the second circuit T_3 , C_3 , and to the input of this second circuit via a capacitor C_4 . The output of the second circuit T_3 , C_3 is connected to the input of the first circuit T_1 , C_1 , T_2 . A capacitor C_2 , connected in parallel to the input of the second circuit T_3 , C_3 , is connected to a current source S_3 , which may, for example, be formed by a cell which is series-connected with a resistor having a high ohmic resistance. The two elementary circuits are supplied by a source S_4 of sinusoidal voltage.

The above-described dividing stage operates as follows:

Let us start from the moment capacitor C_2 is discharged. Transistor T_3 being blocked, voltage v_o from source S_4 appears at point II, thereby rendering transistor T_1 conductive. No voltage therefore appears at point IV and hence at output 19 of the dividing stage. The capacitor C_2 is now becoming charged by source S_3 . As soon as the voltage of capacitor C_2 reaches a value greater than the threshold voltage of T_3 , the voltage at point II will be sufficiently reduced by the current of transistor T_3 . This will cause the voltage to appear at point IV and hence an increase of the voltage at point I, via capacitor C_4 , thereby helping to charge capacitor C_2 to a higher voltage. This will cause transistor T_3 to become fully conductive and transistor T_1 to be blocked. The voltage v_o which will appear at point II will charge capacitor C_p via transistor T_2 , and this will cause, with a certain time lag, transistor T_4 to become conductive and capacitor C_2 to be discharged, i.e. cause the dividing stage to be returned to the state at which the explanation of its operation was started.

FIGURES 13a and 13e respectively show the voltages v_o , v_I , v_{II} , v_{III} and v_{IV} for the case in which the dividing factor is 4.

The frequency dividing circuit shown in FIGURE 14 comprises a certain number of stages of three different types, i.e. those described with reference to FIGURES 8, 10 and 12. This circuit is intended to reduce a high frequency to a very low frequency. The number of stages will obviously depend on the ratio between these two frequencies.

The first stage A of the divider is of the kind illustrated in FIGURE 12. It is connected to a source S_3 of direct voltage via a resistor R and to a source S_4 of sinusoidal voltage whose frequency is to be divided. This first stage A is connected to the next stage B, which is of the kind shown in FIGURE 8, via a decoupling circuit which is supplied by source S_3 and which comprises two series-mounted transistors T_{11} and T_{12} that are respectively controlled by the voltage of output 19 and by that of point II of stage A (see FIGURE 12), i.e. by phase-shifted impulses. The connecting point of transistors T_{11} and T_{12} is connected to the input of stage B. The output 17 of the latter is connected to the following stage B₁, which is of the same kind, via a decoupling circuit which comprises transistors T_{11} and T_{12} preceded by a voltage-amplifying elementary circuit consisting of a transistor T_{13} and of a capacitor C_{13} . These two circuits thus together form a variant of the decoupling circuit which, in fact, is a voltage and power amplifying circuit similar to that disclosed in the above-mentioned patent specification. Stage B₁ is followed by a certain number of stages of the same kind, connected to one another by this second decoupling

circuit, and the output of the last of these stages, B_n , is connected via a decoupling circuit T_{11} , T_{12} to the input of a stage C of the type illustrated in FIGURE 10. This latter stage is followed by a number of stages of the same kind and the output of the last of these stages, C_n , is connected by the decoupling circuit to the output 20 of the divider.

Considering the above explanation about the operation of the FIGURE 1 voltage-amplifying elementary circuit and about the three types of dividing stage comprising such a circuit, the operation of the above-described divider formed thereby will readily be understood. It should, however, still be pointed out that the decoupling circuit formed by transistors T_{11} and T_{12} , besides decoupling the input capacitance of one stage from the output of the preceding stage, also acts as a periodic supply voltage source by converting into such voltage a direct voltage supplied thereto.

It should further be pointed out that the elementary circuits T_{13} , C_{13} comprised by the decoupling circuits of stages B, can be supplied directly by source S_4 .

Clearly, a multi-stage frequency divider could be made up of a single kind of stage, or of two kinds or also of three, as in the case with the divider described by way of example.

FIGURES 15a to 15f respectively show the voltages v_{24} , v_{11} , v_{19} , v_b , v_{17} and v_d .

The described divider only consumes energy for very short periods of time during which the very low capacitance capacitors of these various stages are charged. Thus, if the divider stages B all have the same dimensions, the mean power consumption of each of these stages decreases linearly with the frequency of its supply voltage. The mean power consumption of the divider is thus extremely small.

In view of the ease with which a multi-stage dividing circuit, such as that just described, can be integrated and of its very low energy consumption, it can be utilized with advantage in electronic devices requiring such features, for instance electronic wrist watches.

Although electronic clocks, in particular clocks comprising a quartz oscillator as a regulator (timing means), and further comprising an electronic circuit for dividing the frequency of this oscillator to a suitable value to control a time indicating device, have been known for a long time, no small electronic watch has, as is known, yet been produced. This is due to the difficulties involved in economically producing a dividing circuit of very low energy consumption, which difficulties have been overcome by the present invention.

Another advantage provided by the above-described divider, due in particular to the type A stage (FIGURE 12), destines it even more for use in a small electronic watch. As will have been gathered from the operation of this stage, the capacitor C_2 is charged and discharged in accordance with the periodicity of the sinusoidal voltage while capacitor C_1 is being charged. When transistor T_3 becomes conductive, capacitor C_3 is charged and discharged during one period of voltage v_o whereas capacitor C_1 receives practically no charge at all.

If capacitors C_1 and C_3 both have the same capacitance value, the capacitive load for source S_4 thus remains practically constant. This fact is very important when the periodic voltage source is a high frequency oscillator, such as, for instance, a quartz oscillator.

The load capacity, which is represented by either of capacitors C_1 and C_3 , may be included in a circuit tuned to the inherent frequency of the quartz, thereby making it possible to recover the potential energy of the charge in these capacitors.

An electronic watch comprising an electronic circuit in accordance with the present invention, would thus include for source S_3 a small electric cell, and for source S_4 a quartz oscillator supplying a sinusoidal voltage having, for example, a frequency of about 10^6 c./s. The divider shown in FIGURE 14 would then be adapted in a

manner such that the voltage at its output 20 may have a frequency of about 1 c./s., so as to be able to control a time indicating device.

I claim:

1. An integrated electronic circuit consisting essentially of insulated-gate field-effect transistors of the same conductivity type and of capacitor structure electrically connected in a predetermined circuit arrangement, each of said transistors having first and second electrodes in a conduction path, and a gate electrode for controlling the conductivity of the path, said electrodes being formed on one face of a body of semiconductive material and said first and second electrodes of the transistors having rectifying junctions with said body, and said capacitor structure including a capacitor having first and second electrodes and a dielectric between said first and second electrodes thereof, said capacitor electrodes and dielectric also being formed on said one face of said body, there being a voltage-amplifying elementary circuit having therein a pair of said transistors and said capacitor, the first electrodes of said pair of transistors and of said capacitor being connected to one another, the second electrodes of one of said pair of transistors and of said capacitor being adapted to be connected to the terminals of a periodic supply voltage source, the gate electrode and the second electrode of said one transistor providing the input of said voltage-amplifying elementary circuit and being adapted to be connected to the terminals of a control voltage source, the gate electrode of the other of said pair of transistors being connected to the second electrode of said capacitor, and the second electrode of said pair of transistors being in the output of said voltage-amplifying elementary circuit.

2. An integrated electronic circuit according to claim 1, wherein the source of periodic supply voltage is a source of unidirectional trapezoidal impulses.

3. An integrated electronic circuit according to claim 1 characterized by being a bistable set-reset circuit, having first and second inputs and first and second outputs, and comprising a first said voltage-amplifying elementary circuit formed by first and second said transistors and a first said capacitor, the first electrodes of said first and second transistors and of said first capacitor being connected to one another, the second electrodes of said first transistor and of said first capacitor being adapted to be connected to the terminals of a periodic supply voltage source, the gate electrode and the second electrode of said first transistor providing said first input of said bistable set-reset circuit and being adapted to be connected to the terminals of a control voltage source, the gate electrode of said second transistor being connected to the second electrode of said first capacitor, and the first and second electrodes of said first transistor providing said first output of said bistable set-reset circuit; a second said voltage-amplifying elementary circuit formed by third and fourth said transistors and by a second said capacitor, the first electrodes of said third and fourth transistors and of said second capacitor being connected to one another, the second electrodes of said third transistor and of said second capacitor being adapted to be connected to the terminals of a control voltage source, the gate electrode of said fourth transistor being connected to the second electrode of said second capacitor, and the first and second electrodes of said third transistor providing said second output of said bistable set-reset circuit; a fifth said transistor connected in parallel with said third transistor, the gate electrode of said fifth transistor being connected to the second electrode of said second capacitor, and the first and second electrodes of said third transistor providing said second input of said bistable set-reset circuit; a sixth said transistor connected in parallel with said first transistor, the gate electrode of said sixth transistor being connected to the second electrode of said first capacitor, and the first and second electrodes of said first transistor providing said second output of said bistable set-reset circuit; a seventh said transistor connected in parallel with said fourth transistor, the gate electrode of said seventh transistor being connected to the second electrode of said third capacitor, and the first and second electrodes of said fourth transistor providing said second input of said bistable set-reset circuit; and an eighth said transistor connected in parallel with said fifth transistor, the gate electrode of said eighth transistor being connected to the second electrode of said fourth capacitor, and the first and second electrodes of said fifth transistor providing said second output of said bistable set-reset circuit.

connected to the second electrode of said fourth transistor.

4. An integrated electronic circuit according to claim 1 characterized by being a bistable set-reset circuit, having first and second inputs and first and second outputs, and comprising one said voltage-amplifying elementary circuit formed by first and second said transistors and a first said capacitor, the first electrodes of said first and second transistors and of said first capacitor being connected to one another, the second electrodes of said first transistor and of said first capacitor being adapted to be connected to the terminals of a periodic supply voltage source, the gate electrode and the second electrode of said first transistor providing said first input of said bistable set-reset circuit and being adapted to be connected to the terminals of a control voltage source, the gate electrode of said second transistor being connected to the second electrode of said first capacitor, and the first and second electrodes of said first transistor providing said first output of said bistable set-reset circuit; a voltage-amplifying elementary circuit formed by a third said transistor and a second said capacitor, said third transistor and said second capacitor being connected in series by their first electrodes, their second electrodes being adapted to be connected to the terminals of said periodic supply voltage source, the gate electrode and the second electrode of said third transistor providing said second input of said bistable set-reset circuit and being adapted to be connected to the terminals of a control voltage source, and the first and second electrodes of said third transistor providing said second output of said bistable set-reset circuit; a fourth said transistor connected in parallel with said first transistor, the gate electrode of said fourth transistor being connected to the first electrode of said third transistor; and a fifth said transistor connected in parallel with said third transistor, the gate electrode of said fifth transistor being connected to the second electrode of said second transistor.

5. An integrated electronic circuit according to claim 1 characterized by being a frequency dividing circuit comprising, a plurality of stages each having an input and an output and each including at least one said voltage-amplifying elementary circuit, and further comprising decoupling means connecting the output of one stage with the input of the next stage, said plurality of stages including at least two of the following three types of stage: a low frequency dividing type of stage, a medium frequency dividing type of stage and a high frequency dividing type of stage.

6. An integrated electronic circuit according to claim 5, wherein the medium frequency dividing type of stage includes one said voltage-amplifying elementary circuit, said one voltage-amplifying elementary circuit having therein first and second said transistors and a first said capacitor, the first electrodes of said first and second transistors and of said first capacitor being connected to one another, the second electrodes of said first transistor and of said first capacitor being adapted to be connected to the terminals of a periodic voltage source; a voltage-amplifying elementary circuit having therein a third said transistor and a second said capacitor, said third transistor and said second capacitor being connected in series by their first electrodes, their second electrodes being adapted to be connected to the terminals of said periodic voltage source, and the first electrode of said third transistor being connected to the gate electrode of said first transistor; and a further voltage-amplifying elementary circuit having therein a fourth said transistor and a third said capacitor, said fourth transistor and said third capacitor being connected in series by their first electrodes, their second electrodes being adapted to be connected to

the terminals of said periodic voltage source, the first electrode of said fourth transistor being connected to the gate electrode of said third transistor, and the first and second electrodes of said fourth transistor providing said output of said medium frequency dividing type of stage.

7. An integrated electronic circuit according to claim 5, wherein each high frequency dividing type of stage includes one said voltage-amplifying elementary circuit, said one voltage-amplifying elementary circuit having therein first and second said transistors and a first said capacitor, the first electrodes of said first and second transistors and of said first capacitor being connected to one another, the second electrodes of said first transistor and of said first capacitor being adapted to be connected to the terminals of a periodic voltage source, the gate of said second transistor being connected to the second electrode of said first capacitor and the first and second electrodes of said first transistor providing the output of said high frequency dividing type of stage; a voltage-amplifying elementary circuit consisting of a third said transistor and a second said capacitor, said third transistor and said second capacitor being connected in series by their first electrodes, their second electrodes being adapted to be connected to the terminals of said periodic voltage source, and the first electrode of said third transistor being connected to the gate electrode of said first transistor; a fourth said transistor of which the first electrode is connected to the gate electrode of said third transistor and of which the gate electrode is connected to the second electrode of said second transistor; a third said capacitor connected in parallel with said fourth transistor and being adapted to be connected to the terminals of a direct voltage source; and a fourth said capacitor of which the first electrode is connected to the first electrode of said first transistor and of which the second electrode is connected to the connection between the gate electrode of said third transistor and the first electrode of said fourth transistor.

8. An integrated electronic circuit according to claim 5, wherein said decoupling means comprises a further pair of said transistors which are series-connected by their first electrodes, their second electrodes being adapted to be connected to a direct voltage supply source, their gate electrodes being connected to the output of said one stage and their first electrodes being connected to the input of said next stage.

9. An integrated electronic circuit according to claim 5, wherein said decoupling means comprises a further three said transistors and a further said capacitor, with the first of said further three transistors and said further capacitor being series-connected by their first electrodes, their second electrodes being adapted to be connected to a periodic voltage supply source, with the second and third of said further three transistors being connected in series by their first electrodes, their second electrodes being adapted to be connected to a direct voltage supply source, the gate electrodes of said first and second further transistors being connected to the output of said one stage, the gate of said third further transistor being connected to the first electrodes of said first further transistor and of said further capacitor, and the first electrodes of said second and third further transistors being connected to the input of said next stage.
